UNITED STATES PATENT OFFICE.

JOHN H. KLIEVES, OF WHEELING, WEST VIRGINIA.

DESIGN FOR A BADGE OR BUTTON.

42,050.

Specification for Design.

Patented Dec. 26, 1911.

Application filed October 10, 1911. Serial No. 653,956. Term of patent $3\frac{1}{2}$ years.

To all whom it may concern:

Be it known that I, JOHN H. KLIEVES, a citizen of the United States of America, and resident of Wheeling, county of Ohio, and State of West Virginia, have invented a new, original, and ornamental Design for Badges or Buttons, of which the following is a specification, reference being had to the accompanying drawing, forming part thereof.

The figure is a plan view of a badge or button, showing my new design.

I claim:

The ornamental design for a badge or button, as shown.

In testimony whereof I affix my signature in presence of two subscribing witnesses.

JOHN H. KLIEVES.

Witnesses:

JNO. B. WILSON,
H. E. DUNLAP.
